THERMIONIC VALVE APPARATUS

Richard Lewis Fortescue, London S. W. 12, England, assignor to Standard Telephones and Cables Limited, London, England, a British company, and Marconi's Wireless Telegraph Company Limited, London, England, a British company

Application October 12, 1938, Serial No. 234,535
In Great Britain October 23, 1937

19 Claims. (Cl. 179—171.5)

The present invention relates to thermionic valve apparatus, and is concerned with apparatus which is required to deliver modulated alternating current power to a load.

The invention is particularly applicable to the output stage of a broadcast or like transmitter using low-power modulation, and to other apparatus in which high efficiency, in terms of power conversion of direct current into alternating current, is desired.

A power amplifier which has already been proposed comprises two amplifying valves coupled to a common load and fed with modulated carrier oscillations of the same wave form, one of the two valves having its control grid biased beyond anode-current cut-off so that it is only operative when the amplitude of the applied driving oscillations exceeds the amplitude of the carrier in its unmodulated state. The other valve is biased nearly to anode-current cut-off and consequently amplifies those half-cycles of the modulated carrier wave which drive its grid in the positive sense. One of the valves is coupled directly to the load, and the other is coupled thereto by means of an impedance-inverting network.

An amplifying stage comprising a power amplifier of the type discussed above can be made to have an efficiency substantially greater than that of a normal class C-type amplifier.

Apparatus has also been proposed in which carrier power is supplied to a load by means of a valve coupled directly to the load, and driven by a pure, unmodulated carrier oscillation, additional thermionic valve apparatus being provided to supply further high-frequency power to the load during half-periods when the modulation amplitude is rising, and to absorb power from the load during half-periods of falling modulation amplitude. The additional valve apparatus is coupled to the load through an impedance-inverting network and may take the form of a valve fed with a modulated carrier oscillation comprising no carrier component—that is, pure side-band oscillations.

This invention aims to provide improved highly efficient thermionic valve apparatus for causing a current corresponding to a modulated carrier oscillation to flow in a load.

The invention is concerned with apparatus of the kind in which one valve is coupled to the load through an impedance-inverting network, whereas the other valve is coupled directly in series or parallel to the load.

The present invention accordingly provides ap-

paratus of the kind referred to for causing a current corresponding to a modulated carrier oscillation to flow in a load, said apparatus comprising two thermionic valves coupled to the load and means for applying to their input circuits, driving oscillations of different characters, wherein both driving oscillations include a component of carrier frequency, and wherein the modulation depth of the driving oscillation fed to each valve is different both from that of the driving oscillation fed to the other valve and from that of the oscillation set up in the load.

For the purpose of this specification, the term modulation depth is used to mean the ratio of the amplitude of a particular chosen modulation frequency component to the amplitude of the carrier component, and the preceding paragraph is intended to be read to cover the case in which one valve is driven by an oscillation constituted by an unmodulated carrier, which is taken to have a modulation depth of zero.

The invention also provides apparatus of the kind referred to for causing a current corresponding to a modulated carrier oscillation to flow in a load, said apparatus comprising two thermionic valves coupled to the load and means for applying in their input circuits driving oscillations of different character, wherein both driving oscillations include components of side-band frequencies, and wherein the modulation depth of the driving oscillation fed to each valve is different both from that of the driving oscillation fed to the other valve and from that of the oscillation set up in the load. It is to be noted that in carrying out this aspect of the invention, one valve may be fed with side-band oscillations free from carrier, the modulation depth in this instance being infinite.

In apparatus according to this invention, the two valves may be coupled either in series or in parallel with the load, one directly and the other through an impedance-inverting network. Either or both of the two valves may if desired be replaced by two or more valves connected in parallel, in push-pull, in parallel push-pull, or in cascade; the word cascade is used here to describe arrangements in which two or more valves have their anode-cathode paths in series. In these modifications two of the valves are preferably biased and driven as class C-type amplifiers, and a further pair of valves, similarly arranged but driven in anti-phase, may be coupled to the same load, in order to provide a balanced arrangement and to simplify power supply arrangements. The driving voltages may, of course,

be amplified before application to the two valves, the number of stages of amplification depending on practical requirements.

In the preferred arrangement according to the invention, one of two valves, both of which are coupled to the load, is fed with modulated carrier oscillations in which there is a preponderance of the carrier component, and the other valve is fed with oscillations having a preponderance of the side-band components; the efficiency of the first valve may then be made to approximate that of a continuous wave amplifier, and the other can be made to consume negligible current in the unmodulated carrier condition.

If the required voltage wave form at the load is, for example

$$V[1+\sigma(t)] \sin \omega t$$

where $\sigma(t)$ is a complex quantity representing a complex modulating wave including components which modulate the carrier to different depths, and ω is the carrier frequency multiplied by 2π , then the driving voltages applied to the grids of the two valves may be expressed, respectively, by

$$V_g^1 = V_1[1+\alpha\sigma(t)] \sin \omega t$$

$$V_g^2 = V_2[\beta+\sigma(t)] \cos \omega t$$

where α and β depend upon valve characteristics and circuit constants, and upon the requirements in respect of rectilinearity (with respect to the modulation envelope) and efficiency. The phase difference between these two modulated carriers is necessary in order to compensate for the phase shift of 90° introduced by the impedance-inverting network by which one valve is coupled to the load. The values of α and β are worked out for a special case, by way of example, hereinafter. It is to be noted that although the invention includes the cases in which either α or β is zero, it does not include the case in which both are zero.

In a preferred arrangement, one valve is fed with substantially unmodulated oscillations of the carrier frequency, and is operated so that it has a low apparent internal impedance but is subject to a nearly constant alternating anode voltage, so that it functions as a continuous-wave amplifier with a very high efficiency. The other valve, in the preferred arrangement, is fed with oscillations representing the side-bands of the oscillations which are to be set up in the load, together with a carrier-frequency oscillation of such amplitude that the first-mentioned valve is prevented from driving carrier-frequency current through the second valve. It will be noted that this is the case in which α is zero; under these conditions, β is generally small.

The application of the invention to the output stage of a broadcast transmitter will now be described by way of example with reference to the accompanying diagrammatic drawing. In this application of the invention, the load to which modulated carrier power is to be supplied, is the aerial system.

Figures 1 and 2 illustrate two embodiments of the invention, and Fig. 1a illustrates a modification of Fig. 1, while Fig. 1b shows by label a variation of input content as applied to tube 1. The same references are employed for like parts of all the figures. In Fig. 1 two valves are connected in series with a load and in Fig. 2 two valves are connected in parallel with the load.

Referring to Fig. 1, an output stage comprises two thermionic valves 1 and 2, both valves being

so biased that substantially only those half-cycles of the oscillations applied to them which drive their grids in the positive sense cause anode current to flow. Sources of bias potential, 3 and 4, are provided for this purpose.

The valve 1, which will be referred to for convenience as the carrier valve, has its control-grid coupled by means of a transformer 5 to a source (not shown) of unmodulated carrier oscillations, and its anode is connected through a choke coil 6 to a source (not shown) of anode voltage. The anode of the valve 1 is also connected through a variable condenser 7, an inductance coil 8 and the load 9, all in series, to earth, and the cathode of the valve is also earthed. The load 9 is shown diagrammatically as a resistance. The valve 2 has its control grid coupled by means of a transformer 10 to a source (not shown) of driving oscillations, the nature of which will be further discussed below. The anode of the valve 2, which will be referred to for convenience as the side-band valve, is connected through an inductance coil 11 to the source of anode voltage, and through a condenser 12 and an inductance coil 13 in series to earth, its cathode being also earthed. The two inductance coils 8 and 13 are coupled together by mutual inductance, and each of the variable condensers 7 and 12 is so adjusted as to neutralise the reactance of its associated inductance coil, 8 or 13 respectively, at the carrier frequency when the other coil is open-circuited. The grid of the carrier valve 1 is biased at least to anode-current cut-off, and preferably beyond, whereas the grid of the side-band valve 2 is biased to a point nearly at anode-current cut-off; both valves are operated so as to be conductive during only part of a cycle. The carrier valve may be conveniently biased by means of a grid-leak 16 and condenser 17, as shown in Fig. 1a.

It is to be noted that the two coupled inductances 8 and 13 together with their associated condensers constitute an impedance-inverting network between the side-band valve 2 and the load 9. The arrangement is made such that, in the unmodulated condition, the side-band valve takes no current, and in this condition, the impedance seen looking from the carrier valve 1 towards the load is substantially equal to the load impedance. In the modulated condition, the side-band valve is operative, and the impedance seen by the side-band valve is arranged to be equal to the matched load of this valve, so that the maximum power is supplied to the load.

If the grid voltage of the carrier valve 1 is represented by $v_1 \sin \omega t$, then if the carrier valve is assumed to be of low impedance, its anode voltage will approximate to the constant output voltage $V \sin \omega t$, where

$$\frac{V}{v_1}$$

is the amplification factor of the valve. If the grid voltage of the side-band valve 2 be assumed for the time being to be a pure side-band component, say $-kv_2 \sin \omega t \cos \omega t$, then if this valve is one of high impedance, its anode current can be taken to approximate $-kI \sin \omega t \cos \omega t$, where I is the amplitude of the current caused by a grid voltage v_2 —i. e. where I/v_2 is the mutual conductance of the valve 2. These two approximations ignore the fact that the impedances of the two valves are finite, and account will be taken later in this specification of the finite impedances 75 of the valves. The anode current in the side-band

valve 2 induces across the anode circuit inductance coil 8 of the carrier valve 1 a voltage equal to

$$j\omega M I - kI \sin pt \cos \omega t \approx j\omega M I \sin pt \sin \omega t$$

where M is the magnitude of the mutual inductance between 8 and 13.

The voltage across the load 9, which is the sum of the voltages across the valve 1 and the inductance coil 8, is therefore

$$V \sin \omega t + k\omega M I \sin pt \sin \omega t$$

and if $\omega M I$ is made equal to V , the load voltage becomes

$$V[1+k \sin pt] \sin \omega t$$

which represents a carrier wave of the form $\sin \omega t$ modulated by a modulating wave $\sin pt$ to a depth of modulation k . It will be noted that the depth of modulation in the wave applied to the carrier valve in the case considered is zero, whereas in the wave applied to the side-band valve, the depth of modulation may be regarded as being infinite.

If, as is required, the current in the load 9 is of magnitude:

$$(1+k \sin pt) \cdot \frac{V}{R_1} \cdot \sin \omega t$$

where R_1 is the load impedance, the side-band valve experiences an anode voltage swing which is transferred to it across the mutual inductance coupling, and is given by:

$$\begin{aligned} & j\omega M (1+k \sin pt) \cdot \frac{V}{R_1} \cdot \sin \omega t \\ & = \frac{\omega M V}{R_1} (1+k \sin pt) \cos \omega t \end{aligned}$$

Comparing this anode voltage of the side-band valve with its anode current which was above shown to be approximately $I (k \sin pt) \cos \omega t$, it will be seen therefore, that the side-band valve 2 alternately delivers or absorbs power as the sign of the modulation cycle changes.

In practice, the valves 1 and 2 are both of finite impedance, and to maintain the conditions of constant output voltage from the carrier valve and no current in the unmodulated condition in the other, it is clear that the input voltage supplied to either or both valves must be different from those so far assumed. In the particular embodiment which has been described, it is convenient to modify the input to the side-band valve only, the grid drive supplied to the carrier valve being still a steady carrier wave. The output voltage from the carrier valve can, under these conditions, still be kept very nearly constant, and will vary only slightly with the current in the load.

The required grid drive for the side-band valve is deduced as follows:

The output voltage of the carrier valve 1 is given by:

$$V \sin \omega t - \rho_1 \frac{V(1+k \sin pt) \sin \omega t}{R_1}$$

where ρ_1 is the apparent impedance of the carrier valve. Clearly, ρ_1 should be as small as possible compared to the load impedance R_1 for highest efficiency.

The E.M.F. which has to be induced in the

anode-circuit inductance coil 8 of the carrier valve to main a voltage:

so $\omega M I (1+k \sin pt) \cos \omega t$ may first be

across the load 9 is then:

$$V \cdot k \sin pt \cdot \sin \omega t + \frac{\rho_1}{R_1} \cdot V(1+k \sin pt) \sin \omega t$$

The current required in the inductance coil 13 associated with the side-band valve to induce this voltage is of the form:

$$I \left(1 + \frac{\rho_1}{R_1} \right) k \sin pt \cos \omega t + \frac{\rho_1}{R_1} I \cos \omega t$$

15 The anode voltage swing on the anode of the side-band valve is as before:

$$\frac{\omega M}{R_1} \cdot V[1+k \sin pt] \cos \omega t$$

20 The side-band valve, although operated as a class AB amplifier, can be regarded as a linear amplifier with respect to the modulation envelope, and is therefore subject with regard to this envelope, to the law of superposition. Its grid voltage may therefore be deduced from a

25 knowledge of its anode current and anode voltage swing in two separate parts, (a) that required to prevent the valve taking any anode current under the influence of an anode voltage swing of the form set out above, and (b) that re-

30 quired to produce the desired anode current in the anode circuit coil which, since its inductance is neutralised by its associated condenser, effectively introduces no impedance into the circuit. If the apparent impedance of the side-band valve

35 is ρ_2 , and the apparent magnification factor μ , these parts are:

$$(a) \frac{\omega M}{\mu R_1} \cdot V[1+k \sin pt] \cos \omega t$$

40 and

$$(b) \frac{\rho_2}{\mu} \left[\left(1 + \frac{\rho_1}{R_1} \right) I k \sin pt \cos \omega t + \frac{\rho_1}{R_1} I \cos \omega t \right]$$

45 The grid voltage wave form required in practice with valves of finite impedance, thus becomes:

$$\left[\frac{\rho_2}{\mu} \frac{\rho_1}{R_1} I + \frac{\omega M}{\mu R_1} \cdot V \right] + \text{an anode voltage swing}$$

50 which represents a wave comprising both carrier and side-band components, but having a depth of modulation differing from that of the

55 voltage across the load, and, of course, from that applied to the carrier valve.

With given values of components, the peak anode voltage and current swings, V and I , which are permissible are known, and as already stated,

60 ωM is made equal to V/I . The load resistance R_1 is then determined by the anode voltage swing which is desired on the side-band valve 2, since this voltage swing is equal to:

$$65 \frac{\omega M V}{R_1} [1+k \sin pt] \cos \omega t$$

The current which the carrier valve 1 is re-

quired to supply is then given by:

$$70 \frac{\omega M V}{R_1} [1+k \sin pt] \cos \omega t$$

An advantage of the embodiment of the in-

vention described above is that the carrier valve can be operated as a class C continuous-wave

75 amplifier, and very high efficiency of operation

of this part of the apparatus can therefore be obtained; the efficiency is particularly high when the carrier valve is biased beyond anode current cut-off, as suggested above. The side-band valve takes substantially no current in the absence of modulation, and thus in this condition the efficiency of the apparatus as a whole is very high. It is an advantage to employ valves having characteristics which approximate as closely as possible to the ideal rectilinear characteristic with sharp cut-off, since with such valves, the level of distortion is low.

Because of the finite curvature of the bottom bends of the characteristics of the valves employed in practice, the side-band valve cannot be biased to draw no current in the unmodulated condition. It is, in fact, biased on to the bottom bend, and it may be desirable to convert some of the D. C. power which it absorbs into carrier power. This can be done by increasing the carrier component in its grid drive to a value somewhat greater than that calculated, so that the side-band valve contributes to the carrier power supplied to the load. The power supplied by the carrier valve is then reduced slightly below the value calculated, and high efficiency is maintained.

In a modification of the arrangement shown in Fig. 1, in which the two valves 1 and 2 may each be regarded as being connected in series with the load, the two valves and the load may all be arranged in parallel with one another. This modification is shown in Fig. 2. Any known or suitable means are provided in the two arrangements illustrated to supply the required operating anode, filament and grid bias voltages for the valves, and to reduce the production of radio-frequency harmonics. For example, in Fig. 2, the coupled inductances 8, 13 constituting the impedance inverting network may be shunted by condensers 14 and 15 as shown, which provide low-impedance paths for harmonic voltages, and also form part of the network.

The required grid voltages may be derived by any known or suitable means from sources of carrier oscillations and modulation frequency oscillations, and since these details are not regarded as forming a primary part of the present invention, they have not been illustrated or described. Further, any suitable means may be employed for coupling any desired number of amplifiers according to the invention in push-pull or parallel with respect to a common load, and for feeding suitable driving voltages thereto in suitable phase relationship.

In the above description, the embodiment of the invention considered is one in which both driving oscillations include a carrier component, whereas one of them has no side-band components. This is one limiting case of the invention, the other being that in which both oscillations include side-band components, but one has no carrier component as indicated in Fig. 1b. It will be clear that between these two limits, there is a range of choice of the natures of the two driving oscillations available for carrying out the invention; an example has been given of the method by which the two driving oscillations necessary to cause a given desired current to flow in the load can be determined, and those versed in the art will readily be able to extend the method indicated to cover other cases.

What is claimed is:

1. A system for delivering modulated carrier-wave power to a load, which comprises a first

and a second discharge tube each having a cathode, a grid and an anode, means for supplying continuous potential to said anodes, connections for delivering power from the anodes of both of said tubes to said load, an impedance inverting network connected between the anode of one of said tubes and said load so as to present to the anode of said first discharge tube an impedance whose value decreases with increasing power output from said second discharge tube, means for applying to the grids of said tubes driving oscillations displaced substantially 90° in phase and both said driving oscillations including a component of carrier frequency and only one of said driving oscillations including a component of side-band frequency.

2. Apparatus for delivering modulating carrier-wave power to a useful load, which comprises a first and a second discharge tube each having a cathode, a grid, and an anode, means for applying operating potentials to the electrodes of said tubes, an impedance inverting network having an input and an output, connections from the output of said network to one of said tubes and to said useful load, connections from the input of said network to the other of said tubes, and means for applying to the grids of said tubes driving oscillations displaced substantially 90° in phase and one of said driving oscillations having carrier frequency without side-bands and the other of said driving oscillations including having a carrier frequency and a component of side-band frequency.

3. Apparatus according to claim 2, wherein said means for applying operating potentials to the electrodes of said tubes comprises means for biasing one of said tubes for class C operation and for biasing the other of said tubes for class AB operation.

4. In a modulation system which includes a first vacuum tube for supplying main carrier currents to a load and an auxiliary tube supplying auxiliary carrier currents to said load whose phase with respect to said main carrier currents is controlled by a modulating voltage, the plate of said auxiliary tube being subject to varying potentials due to the main carrier currents in said load, the method of maintaining substantially uniform operating conditions for said auxiliary tube in the presence of said varying plate potentials, which includes the step of controlling the plate current of said auxiliary tube by a radio frequency bias, said bias having a phase which tends to oppose a change in the plate current of said auxiliary tube due to said variation.

5. In a modulation system which includes a first vacuum tube for supplying main carrier currents to a load, and an auxiliary tube supplying auxiliary carrier currents to said load whose phase with respect to said main carrier currents is controlled by a modulating voltage, the plate of said auxiliary tube being subject to varying potentials due to the main carrier currents in said load, the method of maintaining substantially uniform operating conditions for said auxiliary tube which includes the steps of applying to a control electrode of said auxiliary tube a radio frequency bias whose frequency is equal to that of said main carrier, but in phase opposition thereto, and having a potential at least equal to the peak potential of the radio frequency voltage on the plate of said auxiliary tube, due to the main carrier current in said load, divided by the amplification factor of said aux-

illary tube, and controlling the plate current of said auxiliary tube by said derived bias.

6. In combination, a source of main carrier frequency currents, a first amplifier connecting said source to a load, a second vacuum tube amplifier whose output is delivered to said load, said vacuum tube having grid and plate electrodes, means for applying modulating voltages to said grid, means for energizing said grid by a radio frequency voltage whose phase is determined by said modulating voltages whereby the resultant current in said load is determined by said modulating voltages, and means for applying a radio frequency bias to said grid to compensate for varying plate potentials applied to said second amplifier due to voltages across said load.

7. The combination which includes a source of main carrier frequency currents, a first triode amplifier connecting said source to a load, a second triode amplifier having a plate and grid electrodes whose output is delivered to said load and whose plate is affected by the voltage across said load due to currents from said first amplifier, means including said second amplifier for impressing currents across said load whose phase with respect to currents in said load from said first amplifier is determined by a modulating signal, and means for maintaining constant anode current in said second amplifier in the absence of said modulating signal.

8. The combination which includes a source of main unmodulated carrier frequency currents, an antenna, a first triode amplifier connecting said source to said antenna, a second triode amplifier having plate and grid electrodes whose output is delivered to said antenna and whose plate potential is affected by the voltage across said antenna, means for applying modulating voltages to said grid, means for energizing the grid of said second triode by a voltage which produces output currents in phase with currents in said antenna due to said first amplifier when said modulating voltage is of one polarity, and output currents out of phase with currents in said antenna due to said first amplifier when said modulating voltage is of the other polarity, and means for maintaining constant plate current in said second amplifier in the absence of said modulating voltages.

9. A device of the character described in claim 8 which is further characterized in that said means for maintaining constant plate current is a radio frequency bias.

10. The combination which includes a source of main carrier frequency, an antenna, a first triode amplifier and an impedance inverting network connecting said source to said antenna, means for applying modulating voltages to said grid a second triode radio frequency amplifier having grid and anode electrodes, means for impressing the output of said second triode amplifier across said antenna, the phase of the radio frequency output of said second amplifier being determined by said modulating voltages, and means for causing said second triode amplifier to deliver the same amount of radio frequency current to said antenna independently of the potential appearing on said anode due to currents in said antenna from said first amplifier.

11. Apparatus for causing a current corresponding to a modulated carrier oscillation to flow in a load, said apparatus comprising two thermionic valves, each coupled to said load and one of them being coupled to the load through

an impedance inverting network, and means for applying to the input of one valve a driving oscillation having no substantial side-band components and means for applying to the input of the other valve a driving oscillation comprising a carrier frequency and side-band components, said driving oscillations being displaced substantially 90° in phase from each other.

12. Apparatus according to claim 11 in which 10 a valve having no substantial side-band components has its control grid biased beyond anode current cut-off.

13. Apparatus according to claim 11 wherein 15 the impedance inverting network comprises two inductance coils coupled by mutual inductance.

14. Apparatus for causing a current corresponding to a modulated carrier oscillation to flow in a load, said apparatus comprising two thermionic valves, one of which is coupled to the 20 load through an impedance inverting network and the other of which is coupled directly to the load, means for applying to the input circuits of said valves driving oscillations of different character displaced substantially 90° in phase from each other, one of said driving oscillations comprising a carrier frequency without side-band components and the other of said driving oscillations comprising a carrier frequency and side-band components, but principally side- 25 band components.

15. Apparatus for causing a current corresponding to a modulated carrier oscillation to flow in a load, said apparatus comprising two thermionic valves, each coupled to said load and one of them being coupled to the load through an impedance-inverting network, and means for applying to the input of one valve a driving oscillation having a carrier frequency and side-band components and means for applying to the input 35 of the other valve a driving oscillation having a side-band component with a different depth than the side-band component on the first valve, said driving oscillations being displaced substantially 90° in phase from each other.

16. Apparatus for causing a current corresponding to a modulated carrier oscillation to flow in a load, said apparatus comprising two thermionic valves, one of which is coupled to the load through an impedance-inverting net- 40 work and the other of which is coupled directly to the load, means for applying to the input circuits of said valves driving oscillations of different character displaced substantially 90° in phase from each other, each of said driving oscil- 45 lations comprising a modulated carrier frequency, the modulation depths of which differ from each other and at least one of said driving oscillations comprising a substantial amount of carrier frequency wave energy.

17. A system for delivering modulated carrier wave power to a load, which comprises a first and a second discharge tube each having a cathode, a grid and an anode, means for supplying continuous potential to said anodes, connections 50 for delivering power from the anodes of both of said tubes to said load, an impedance inverting network connected between the anode of one of said tubes and said load so as to present to the anode of said first discharge tube an impedance 55 whose value decreases with increasing power output from said second discharge tube, means for applying to the grids of said tubes driving oscillations displaced substantially 90° in phase, one of said driving oscillations including a component 60 of carrier frequency and a component of

side-band frequency, and the other of said oscillations including a component of side-band frequency of different modulation depth than the first mentioned component of side-band frequency.

18. A system for delivering modulated carrier-wave power to a load, which comprises a first and a second discharge tube each having a cathode, a grid and an anode, means for supplying continuous potential to said anodes, connections for delivering power from the anodes of both of said tubes to said load, an impedance-inverting network connected between the anode of one of said tubes and said load so as to present to the anode of said first discharge tube an impedance whose value decreases with increasing power output from said second discharge tube, means for applying to the grids of said tubes driving oscillations displaced substantially 90° in phase, both said driving oscillations including a component

of side-band frequency and only one of said driving oscillations including a component of carrier frequency.

19. Apparatus for causing a current corresponding to a modulated carrier oscillation to flow in a load, said apparatus comprising two thermionic valves, one of which is coupled to the load through an impedance-inverting network and the other which is coupled directly to the load, means for applying to their input circuits driving oscillations comprising components of the said modulated carrier oscillation, the oscillations of the two input circuits being displaced substantially 90° in phase, the oscillations fed to one input circuit comprising a preponderance of carrier component and the oscillations fed to the other input circuit comprising a preponderance of side-band content.

RICHARD LEWIS FORTESCUE.
